UNITED STATES PATENT OFFICE.

ALBERT DELAS, OF PARIS, FRANCE, ASSIGNOR TO DELAS CONDENSER CORPORATION, OF NEW YORK, N. Y., A CORPORATION OF DELAWARE.

REFRIGERATING MACHINE.

Application filed January 24, 1920, Serial No. 353,865, and in France June 25, 1919. Renewed October 23, 1926.

- The present invention relates to refrigerating apparatus employing water vapor as the refrigerating fluid and has for one of its principal objects to provide a form of apparatus in which the friction of the fluid on movable elements is employed to create the difference or a part of the necessary difference of pressure between the evaporator and the condenser of the apparatus.
- 10 The successful use of water as the refrigerating fluid involves high ratios of compression and at the same time the handling of considerable resultant volumes. The ratio of compression is approximately six times that of ammonia systems and the resultant suction volume six hundred times.
- Attempts to employ centrifugal aspirators for this purpose, for which they seem adapted because of their great suction volume, 20 proved unsuccessful due to the magnitude of the viscosity of water vapor with relation to its low density at low pressures. This relation between the viscosity and density is such that the pressure lost through friction is 25 very much greater than the pressure produced by centrifugal action.
- It has also been proposed to create the desired difference of pressure by employing the friction of a steam jet in devices known as 30 ejectors. In such systems the steam consumption of the first stage ejector is considerable. Furthermore, unless intermediate condensers are employed, the weight of the steam or other motive fluid of the first stage is added 35 to the weight of the entrained fluid passing through the later stage or stages so that the work in the later stages is multiplied in almost impossible proportions.
- In accordance with my invention the difference in pressure or the first stage of the 40 difference in pressure required to evacuate the evaporator is obtained by entraining the water vapor by frictional contact with mechanically actuated moving walls or surfaces.
- 45 Referring to the drawings which illustrate what I now consider preferred forms of my invention:
- Figure 1 is a diagrammatic view illustrating one way in which the friction compressor 50 may be driven.
- Figs. 2 and 3 are respectively a side and front elevation, in section, of a preferred form of frictional compressor or pump.
- 55 Referring to Fig. 1, the evaporator *a* receives water in the form of a spray through the pipe *b*. The water vapor is withdrawn through the pipe *c* by the friction pump *d* connected thereto. From the pump the vapor, as will more fully hereinafter appear, is conducted to a condenser *e*, the water of condensation being emptied from the latter by a suitable pipe or outlet. Among other forms of suitable friction pumps the one illustrated in Figs. 2 and 3 may be employed.
- 60 The last-mentioned pump comprises a casing *d* having a fluid inlet opening *r* and an outlet opening *s*. A shaft *k* is rotatably mounted in said casing and has secured thereto a spider *u* having fixed thereon a series of spaced discs *l*. A plurality of sets 65 of spiral baffles *m* are fixed to the casing *d*, each set being interposed between a corresponding pair of discs *l*. It will be noted that the clearance between the discs *l* and spirals *m* is comparatively small. By virtue 70 of this construction a plurality of bent tubes are provided, each tube having a rather flat rectangular transverse section in which the small sides are stationary while the large or longer sides formed by the discs move at 75 great speed on rapid rotation of the shaft *k*. On rotation of said shaft motion is imparted to the fluid entering at *r* and the fluid leaves at *s*. In this way one can obtain an entrainment of the fluid in the direction of the 80 arrows by friction over a large area, by proportioning at each instant the transverse section of each tube to resultant pressure.
- 75 The pump *d* instead of discharging directly into the condenser may be caused to 85 discharge through the turbine. Furthermore, the motive fluid of the turbine may be supplied from an ejector. Both of these features are embodied in the system shown in Fig. 4. The exhaust vapor from the compressor or friction pump *d* travels in the direction of the arrows into the ejector *g* when it comes into contact with the motive fluid entering at *g'* and is entrained. The mixture so formed is supplied to and propels 90 the turbine which in turn mechanically drives the pump *d*. The turbine exhausts into the condenser *e*. It will be obvious that the pump *d* effects the first stage compression and the ejector *g*, the second stage.
- 95
- 100
- 105
- What I claim is:
1. In combination, a pump, a motor for driving said pump, an ejector into which

- said pump discharges, means for supplying motive fluid to said ejector, and means for conducting the discharge of said ejector to said motor to drive the latter.
5. 2. In combination, a friction pump for withdrawing gaseous fluids, an ejector into which said pump discharges, means for supplying motive fluid to said ejector, a turbine driven by the discharge of said ejector and connected to said pump to drive the latter, and a condenser into which said turbine discharges.
- 10 3. An apparatus for producing high vacuums comprising a friction pump, a turbine for actuating said pump, in combination with a fluid actuated ejector through which the fluid from said pump is exhausted, and means for connecting said ejector with said turbine for actuating the latter.
- 15 4. An apparatus for producing high vacuum comprising a compressor communicating with the chamber to be exhausted, a turbine for actuating said compressor, in combination with a fluid actuated ejector the inlet of which is connected to the exhaust of said compressor and the outlet of which is connected to said turbine to actuate the latter.
5. An apparatus for producing high vacuums comprising a fluid actuated ejector for producing a moderate vacuum, in combination with means actuated by the motive fluid from said ejector for entraining the gas in that vacuum.

In testimony whereof I hereunto affix my ³⁵ signature.

ALBERT DELAS.
